UNITED STATES PATENT OFFICE.

JERVIS R. HARBECK, OF DETROIT, MICHIGAN, ASSIGNEE TO AUTOMAT CAR COMPANY,
OF DETROIT, MICHIGAN, A CORPORATION OF MICHIGAN.

HINGED-COVER CONTAINER.

1,148,878.

Specification of Letters Patent. Patented Aug. 8, 1915.

Application filed November 25, 1910. Serial No. 362,686.

To all whom it may concern:

Be it known that I, JERVIS R. HARBECK, a citizen of the United States, residing in Detroit, in the county of Wayne and State of Michigan, have invented a new and useful Improvement in Hinged-Cover Containers, of which the following is a specification.

My invention relates to improvements in containers, and more particularly to containers having paper or fibrous bodies and sheet metal heads.

The object of the invention is to provide a fibrous body container having a hinged head or cover, which will be of a simple and efficient construction, composed of few parts and capable of being cheaply manufactured.

This result I accomplish, and herein my invention consists, by providing the paper or fibrous body of the container with an integral hinge member at one end, divided from the main portion of the body by short, longitudinal slits, the body being transversely creased at the base of its integral hinge member to adapt the hinge member to turn at its creased portion without breakage or injury, and combining therewith a metallic cover having a flange furnished with integral tangs clenched to the hinge member of the fibrous body.

My invention further consists in the novel construction of parts and devices, and in the novel combinations of parts and devices herein shown and described and more particularly specified in the claims.

In the accompanying drawing forming a part of this specification, Figure 1 is a perspective view of a hinge cover fibrous body container embodying my invention. Fig. 2 is a rear elevation. Fig. 3 is a side elevation showing the cover open. Fig. 4 is a vertical section on line 4—4 of Fig. 2. Fig. 5 is a vertical or longitudinal section on line 5—5 of Fig. 4. Fig. 6 is a detail, horizontal section on line 6—6 of Fig. 5 and Fig. 7 is a detail perspective view of the sheet metal cover before being attached to the paper body.

In the drawing, 1 represents the paper or fibrous body of my improved container, the same being preferably oblong in cross section, and having substantially flat back and front walls 2, 3 and rounded side or edge walls 4, 5.

6 is the sheet metal bottom head of the

container, the same having inner and outer flanges 7, 8 embracing and slightly clamped upon the lower end of the fibrous body to firmly secure the same thereto.

The paper or fibrous body 1 is provided at its upper end with an integral hinge member 9, separated from the main portion of the body by short, longitudinal slits 10, and having an inwardly projecting crease 11 at its base or junction with the main portion of the body to adapt the hinge member to turn at such crease as a pivot without breakage or injury.

12 is the hinged sheet metal cover or top head of the container. It is provided with an integral depending flange 13, adapted to surround and embrace the upper or mouth end of the body. At its back and front portions, the flange 12 of the cover is made materially deeper than at the rounded end portions 14 thereof. The cover thus has an inclined lower edge 15 at its rounded end portions which facilitates the closing of the hinged cover over and around the upper or mouth end of the paper body. To further facilitate the closing of the cover, its flange 13 is provided at the front portion 16 thereof with an outwardly turned lip 17, which enables it to close over the front end edge of the body without fraying or marring the same or the label thereon. The flange of the cover at its back portion 18 is provided with integral tangs or tongues 19 which are inserted through the integral hinge member 9 of the body and their projecting ends clenched down, thus firmly and rigidly uniting the cover to the integral hinge member of the body.

The deep portion of the cover flange at the back serves to overlap and close the short slits 10 in the body, and the straight horizontal lower edge of this portion of the cover flange reinforces the hinge member 9 of the body and causes it to pivot or turn at the horizontal, inwardly projecting crease 11.

I claim:

1. A container having a soft, paper-walled body provided with an integral hinge member slidden in its end portions at the top thereof and adapted to be bent, and a cover having a depending flange extending entirely therearound and adapted to fit over the body, said flange, at one portion thereof, being provided with integral tangs inserted

through and clenched upon said hinged member of the body, substantially as specified.

2. A container having a stiff, paper-walled body provided with an integral hinged member slit from the back of said body below the top edge thereof and adapted to be bent outward, and a cover having a depending flange extending entirely around

the top end of the said body and adapted to fit over the same, the rear of said depending flange being attached to said hinged member of the body to turn therewith, substantially as specified.

JERVIS R. HARBECK.
